UNITED STATES PATENT OFFICE

CARL H. JOHANSON, OF LOS ANGELES, CALIFORNIA

FOURCHETTE-LESS DUPLEX-FINGER SYSTEM GLOVE

Application filed August 24, 1931. Serial No. 558,905.

This invention relates to gloves.

It is an object of the present invention to provide a dress glove which is entirely without fourchettes of any kind and more especially it is an object to provide an improved method for the production of glove blanks in which the roots or crotches of the fingers are so peculiarly cut and outlined that when the fingers of the front and back, that is the palm and the back parts of the glove, are stitched edge to edge without the introduction of any intermediate fourchette, the hand can be readily inserted into the wrist of the glove and the fingers passed readily into the finger sacks. By practical demonstration of the present method gloves have been produced by the use of palm and back patterns which when sewed obtain a highly satisfactory fit of the finger sacks upon the several fingers and upon the thumb.

By the present method a glove of exceptionally low cost of manufacture and sale price is produced and, further, a glove is obtained which can be worn on either hand with good fit and comfort.

In the manufacture of gloves according to the present method the fingers of the palm and back blank portions, whether these are joined in one piece or produced in two separate blanks, are substantially duplicate and only a slight difference is made in the thumb blank portions so as to bring the seam connecting them into a desired position along the ball of the thumb.

A further feature in the production of the glove is the peculiar relation of the base line of the wrist to the base line of the thumb and the peculiar curvature of the side line of the glove between the base of the little finger and the relative end of the base line of the wrist.

The invention consists in certain advancements in this art as set forth in the ensuing disclosure and having, with the above, additional objects and advantages, and whose construction, combination and details of means, and the manner of operation will be made manifest in the description of the here-with illustrative embodiment; it being understood that modifications, variations and

adaptations may be resorted to within the scope, principle and spirit of the invention as it is more directly claimed hereinafter.

Figure 1 is a plan showing superposed sewed palm and back blanks for the manufacture of a glove by the improved method utilizing two pattern pieces each having a complete duplicate set of fingers and nearly duplicate thumbs.

Fig. 2 is a plan of a composite blank having duplicate finger systems for palm and back and provided with a thumb hole; the finger system of this pattern being identical with the finger system of the pattern shown in Fig. 1.

Referring to the two-piece glove shown in Fig. 1 the palm piece 2 is shown as stitched on a back piece 3, the former having a thumb part 4 and the latter having a thumb part 5 which is shown as slightly out-curved at 6 to form a desired fullness of the thumb and bring the seam down well inward toward the palm rather than have it along the outside line of the thumb as would be the case in absence of the differential fullness 6.

For the purpose of description a base line *a*—*b* is extended from the thumb side of the first finger 8 through the thumb to about its base line *c*. It will be seen that the first finger 8 is materially curved on thumb side and its end 19 bends somewhat away from the base line *a*—*b* toward the contiguous second finger 9 which lies along the third finger 10 on a substantially straight line 11 and the little or fourth finger 12 lies at its outer position parallel to finger 10 along line 13 which is materially curved at 14 inwardly under the finger 10. The outside edge of the little finger 12 is re-entrant on line 15 to a point about opposite the base of the thumb 4 whence it curves outwardly on a flaring line 16 which extends to the wrist base line 17.

The base line 17 extends transversely and has an inclined line 18 springing toward the thumb base *c*. It will be noticed that the line 18 diverges from the base line *c*—*b* to the wrist line 17 and presents an oblique wrist zone 20 with respect to the base line *a*—*b*.

Again referring to the fingers 8, 9, 10 and 12 it will be noted that the line of separa-

100

tion is substantially straight to the root or crotch of the finger blank and that the root line 14 of fingers 10-12 curves inwardly toward the center of the palm 2. On the contrary, the line 21 of separation between the fingers 8 and 9 terminates in a slightly curved root 19 bearing toward the axis of the finger 9. Correspondingly the outside edge 22 of the finger 8 has a long convex curve toward the center of the palm and away from the base line *a-b*.

This unique and peculiar cutting of the roots of the fingers is found to provide ample entry clearness for the insertion of the fingers of the hand, into a corresponding size glove.

When the palm blank 2 and the back blank 3 are sewed together, inside out, closely around the margins, except across the wrist line 17, and when the sewed glove is turned inside out so as to bring the seamed margins internally, the glove very accurately fits a hand of corresponding size without any difficulty in the insertion of the hand or entry 25 of the fingers into the finger sacks.

While Fig. 1 shows a two piece glove including thumb parts 4 and 5, which may or may not be cut of one piece with the palm and back blanks, there is shown in Fig. 2 30 a one-piece glove blank comprising a palm area 2 and a back area 3 each of these having complementary portions 12-12, 10-10, 9-9, and 8-8.

A thumb hole 25 is provided in the blank 35 for the attachment of a thumb in an old and well-known manner. However, the fingers of this one-piece blank are cut and sewed on the same system as hereinabove set forth in the description as to the glove as shown 40 in the Fig. 1.

The object of the deeply incurved little finger side line 15-16 is to obtain a very close fit of the glove along the little finger side of the hand when inserted.

45 Gloves can be made by this method and on patterns of the type here shown by the utilization of any desired material such as leather, knit goods or warp and weft fabrics. An important advantage is that no fourchettes are required and the sewing of 50 the parts of the gloves is greatly simplified since it is only necessary to closely sew around the margins of the sides of the wrist, the thumb, and the fingers as shown at S.

55 The purpose of the incurves at the base of the little finger and of the forefinger is to eliminate bagginess common to previously proposed types of gloves made without fourchettes.

60 By dress glove I mean to include all types of gloves of hand fitting case, as distinguished from stuffed and padded gloves.

What is claimed is:

65 1. A glove including palm and back parts each having substantially duplicate finger

width systems, in which the roots of the first and fourth front and back fingers incurve toward the center of the palm; the palm and the back being of equal width.

2. A glove including equal width palm and back parts each having substantially duplicate finger width systems, in which the roots of the first and fourth front and back fingers incurve toward the center of the palm, and the second and third fingers have a straight intermediate root line.

3. A glove having systems of duplicate palm and back finger covers and in which the area of the fingers of each system are co-extensive, and in which the root lines between the first and second fingers and between the third and fourth fingers each curve toward the center of the glove so that when stitched on their lines the fingers are in proper position for application to the hand and free from undesired back fulness.

4. A fourchette-less glove including duplicate palm and back blanks which have forefinger and little finger covers each of which have their inside root edges materially incurved toward the center of the glove so as to eliminate bagginess across the base line of the finger system and to bring the finger holes into proper position when the blanks are stitched; the finger parts of the palm and of the back being duplicate.

5. A fourchette-less glove including substantially duplicate palm and back covers, each of which are provided with a system of finger parts, those of the palm being the duplicate of those of the back, and the first, the second and the fourth fingers having their root parts materially curved inwardly toward the central body of the glove, the cuts of the first and second fingers and the cuts of the third and fourth fingers being characterized in the glove blanks by slits which extend from the extremities of the fingers and at the inner ends of the fingers proper, curve toward the center of the glove.

6. A glove including duplicate front and back portions, each with finger blanks, the second and third finger blanks of each portion being separated by a straight slit to their relative root, the remote sides of said fingers being separated from their adjacent first and fourth fingers by slits which bend materially inward so that the second and third fingers are appreciably widened to provide fulness for a finger without making dart incisions in the said portion and without use of fourchettes.

7. A glove including duplicate front and back portions, each with finger blanks, the second and third finger blanks of each portion being separated by a straight slit to their relative root, the remote sides of said fingers being separated from their adjacent first and fourth fingers by slits which bend materially inward so that the second and third is

fingers are appreciably widened to provide fullness for a finger without making dart incisions in the said portion and without use of fourchettes; the base of each little finger curving, along each of its sides, inward as to the third finger base.

CARL H. JOHANSON.
